ANCHOR

Hardwick Price Shipley, Falls Church, Va.

Application April 15, 1944, Serial No. 531,239

1 Claim. (Cl. 114—208)

(Granted under the act of March 3, 1883, as
amended April 30, 1928; 370 O. G. 757)

1

This invention relates to anchors and more specifically to anchors for water-borne vessels.

In general it is an object of the invention to provide a device which is simple of construction, easily and readily manufactured, prompt and efficient in operation, sturdy and of long life.

Another object of the invention is to provide an anchor which has a positive digging-in function prior to the gripping of the flukes which assists the latter and which positively rotates the flukes to an initial gripping position and positively increases their gripping position to the optimum position for holding so that they do not pull out of the ground; to provide means for such preliminary digging-in which are of extreme simplicity and which do not clog, and to provide such means which also control the maximum fluke-shank angle.

Another object is to provide an anchor with a stock which may be used at the crown or at the forward end whereby the stock is interchangeable and may be used at either end of the shank thereby permitting hawse-pipe stowage when the stock is in the after end and increased efficiency with the stock at the forward end, especially in the latter case when used with anchor cables of inadequate weight such as fiber and wire ropes, the weight of the stock tending to hold the shank horizontal.

Other objects of the invention will, in part, be obvious and will, in part, appear hereinafter.

The invention accordingly comprises articles of manufacture possessing the features, properties and relation of elements that will be exemplified in the articles hereinafter described, the scope of the application of which will be indicated in the claims.

For a better understanding of the invention, reference should be had to the following description taken in connection with the drawing, in which:

Fig. 1 is a plan view of an anchor embodying one form of the invention;

Fig. 2 is a side view of the anchor shown in Fig. 1, the crown and the stock being shown in cross section;

Fig. 3 is an after end view of the anchor shown in Fig. 1;

Figs. 4—6 are views, similar to those of Figs. 1—3, of a modification of the anchor shown in Figs. 1—3; and

Fig. 7 is a perspective view of another modification.

When an anchor is first pulled along the surface of a sea bed into which it is to grip there is a tendency for the flukes to ride along that surface. There is no gripping until their forward edges do cut down into that surface and when the cutting-in is left to chance it has been found that an anchor may be pulled a considerable dis-

2

tance before it begins to operate and in some instances it may pull out even after it has once started to grip. The anchors described below have special parts, which, by providing a rotational moment, force the forward fluke edges to assume an angle such that they are forced down into the ground by the reactionary force of the ground as the anchor is pulled forward. They are not only brought to that angle but that angle is increased by the action of those parts until the flukes finally have so much of their forward faces under the surface that their own action causes them to sink deeper and deeper to give a complete grip.

In Figs. 1—3, 10 denotes a shank having, at right angle therethrough, an aperture 12 at the forward end and an aperture 14 at the after end, each adapted to receive therethrough a stock 16. Flukes 18 are attached to and integral with a crown 20 which comprises two side pieces 22 more or less parallel with the shank and positioned one on each side thereof. Apertures 24 in side pieces 22 are aligned with aperture 14. The stock extends through apertures 14 and 24. The flukes and crown are oscillatable about the stock, as is the shank, and independently thereof. When the stock is at the forward end of the shank an axle piece may take its place at the after end. When the plane of the flukes is parallel with the longitudinal axis of the shank, the position of all of said parts is called, herein, neutral. As shown in Figs. 2 and 5 the center of gravity of the crown in neutral position is at least as far forward as its axis of oscillation.

On each side of the shank and connecting the two side pieces 22 of the crown are digging elements 26 each of which has an inner surface 28. The latter surfaces define a dihedral angle of from about 30° to about 80° and preferably about 60°. Their after edges are spaced from each other and from any central after cross piece 30 which may be present between the side pieces. The forward edges of elements 26 may be sharpened. This assists the digging in.

Extending inwardly from each surface 28 or preferably, and as shown, extending toward those faces and integral with the shank are protuberances 32, each having a surface against which the respective surface 28 seats. The height of the protuberance is such that, when surface 28 seats thereagainst, the other surface 28 is at an angle in the range of about 30°—80°, preferably about 60°, with the longitudinal axis of the shank and the flukes are beneath and at an angle of between 20°—40°, preferably 30°, with the shank. The bearing surfaces of the protuberances 32 may be broader than the main body thereof; i. e., the protuberances may be streamlined, as shown in Fig. 3, to permit the ready passage thereby of ground material.

The operation of the above anchor is as follows. The anchor is deposited upon the ground or sea bed. The forward tips of the flukes drop just below the shank until they touch the ground, but do not necessarily grip since they make an angle of only some 15° with the horizontal ground-line. The forward edges of digging elements 26 are against the ground, the surfaces 28 making a total of 45° angle with the ground (30° plus the 15° which the crown has been tipped by the 15° drop of the flukes to which the crown is attached).

As a forward force is imparted to the anchor, the surface 28, being at said angle of about 45° with the horizontal ground-line, aided by its sharpened forward edge, begins to penetrate. As penetration of the ground by surface 28 proceeds, the reaction of the ground on said surface creates a torque on the crown and attached flukes tending to rotate the flukes, about the stock or pivot pin, downward into the ground. After this initial engagement of the flukes has been accomplished, the torque developed by the action of the ground on surface 28 combines with the torque due to the downward component of the ground force on the flukes and assists in rotating said flukes into their final operative angular position of approximately 30° with the centerline of the shank.

Since the resistance to forward motion of a flat surface in the ground is obviously a function of its area projecting onto a vertical plane, it can be seen that the resistance to forward motion of a surface of given area increases as the plane of the surface approaches the vertical. Hence, since the surface 28 assumes, preferably, an angle of approximately 60° with the horizontal when the flukes are in their final operative position, said surface provides an important supplementary source of holding power, when the flukes are in said final operative position.

During the action described above, which culminates in said final operative position, clogging of the crown has been prevented because the after edges of the surfaces 28 are widely displaced from each other and other internal obstructions to permit ground material to pass through the crown during the brief forward and downward disposition of the anchor to final gripping position. As shown in Fig. 2 that portion of the operative surface 28 which is nearest to the rocking axis of the crown is still spaced away from the rocking axis by a distance which is greater than the projected area of the digging element 26. Should the foremost and rearmost edges of the digging element 26 be projected onto a plane perpendicular to the plane of the flukes, it will be found that the distance measured along the perpendicular plane between the projections of these edges is less than the narrowest part of the passageway through the crown; namely, that part of the passageway defined by the distance from the rocking axis of the crown to the rearmost edge of surface 28. Experimentation with various size models and with actual anchors have shown that this relation between the projected size of the digging element and the size of the passageway through the crown is necessary to enable the free movement, through the crown, of the material dug up by the element 26. The passageway may vary with various weight anchors, but in all cases the passageway, in its narrowest portion, remains larger than the projected area of element 26.

In Figs. 4-6 there is shown a modification in which there are no protuberances but the function of the latter is provided by a surface 34 on cross elements 36 which extend between the side pieces 22. The surfaces 34 are similar to surfaces 28 except that they form a dihedral angle, the apex of which is spaced from the dihedral angle apex of the surface 28 and coincident with the centerline of the flukes and in the region of and normally slightly aft of the axis of the apertures 14. As a result, when the flukes rotate to a position below the shank, surface 34 approaches and abuts against the upper surface of the shank which may be taken parallel to the shank longitudinal axis. At such latter time the plane of the flukes is at approximately 30° with that shank axis. The dihedral axis position, the angle between surfaces 34, and the shank surface position may be varied inter se in different anchors so that the maximum fluke-shank angle is 30°. Clogging about elements 36 is prevented by the fact that they are spaced from elements 26 and their after edges are spaced from each other.

The operation of the anchor of Figs. 4-6 is evident when the design and operation of the anchor of Figs. 1-3 is considered.

In Fig. 7 there is shown a modified crown having an I-shaped structure above and an I-shaped structure below the shank. The digging in surfaces 128 are at an angle with each other of approximately 60°, and the angle-limiting surfaces 134 perform the functions of surfaces 28 and 34 of the anchor in Figs. 4-6 and are similarly oriented. The surfaces 128 and 134 are provided by the I-shaped structures as shown.

The invention described herein may be manufactured and used by or for the Government of the United States of America for governmental purposes without the payment of any royalties thereon or therefor.

What I claim as new is:

An anchor comprising a shank, a pair of flukes, and a crown oscillatable with said flukes and having a pair of surfaces that are at an angle of approximately 30-60 degrees with each other and that slope rearwardly toward each other and that face each other, said crown having a second pair of surfaces similar to said first pair except that the apex of the dihedral angle of the second pair is spaced from the apex of the angle of the first pair and is approximately at the axis of rotation of said crown, said crown comprising an I-shaped structure above said shank and a second I-shaped structure below said shank.
